CLAIM

The ornamental design for a cigar holder, as shown and described.

DESCRIPTION

FIG. 1 is a perspective view of a cigar holder showing our new design;

FIG. 2 is a top view thereof;

FIG. 3 is a bottom view thereof;

FIG. 4 is a side view thereof;

FIG. 5 is a rear view thereof; and,

FIG. 6 is front view thereof.

The broken lines are for illustrative purposes only and form no part of the claimed design.

1 Claim, 4 Drawing Sheets
